ELECTRIC TOASTER FOR WALL OR COUNTER TOPS

Frank R. Swanson, 607 Washington Ave., Owosso, Mich.

Filed Apr. 15, 1963, Ser. No. 74,439

Term of patent 14 years

(Cl. D81—10)

Fig. 2

Fig. 1

Fig. 3

Fig. 4

Fig. 5

FIG. 1 is a front face elevational view of an electric toaster for walls or counter tops showing my new design.

FIG. 2 is a top plan view thereof.

FIG. 3 is an end elevational view, and

FIG. 4 is an opposite end elevational view.

FIG. 5 is a sectional, horizontal view through the control plate taken on the line 5-5 of FIG. 1.

The rear of the toaster is substantially flat and unornamented.

I claim:

The ornamental design for an electric toaster for wall or counter tops, substantially as shown and described.
